UNITED STATES PATENT OFFICE.

RALPH A. WAXLER, OF LAWRENCEVILLE, ILLINOIS.

SAFETY GAS CUT-OFF.

1,091,991.

Specification of Letters Patent. Patented Mar. 31, 1914.

Application filed December 6, 1913. Serial No. 805,148.

To all whom it may concern:

Be it known that I, RALPH A. WAXLER, a citizen of the United States, residing at Lawrenceville, in the county of Lawrence 5 and State of Illinois, have invented new and useful Improvements in Safety Gas Cut-Offs, of which the following is a specification.

This invention relates to safety cut-offs 10 for gas service systems, such as a house service system, the object of the invention being to provide an automatic, pressure-controlled cut-off valve which will remain open until the gas pressure falls to a predetermined 15 point and will then close and cut off the supply of gas to the building, thereby preventing danger of the escape of gas from open fixtures within the building in the event of the extinguishment of the flame by 20 a reduction of gas pressure in the service system.

A further object of the invention is to provide a cut-off including a valve which when once closed must be positively opened 25 and latched in opened position, in order that a supply of gas to a building from which the gas has been cut off by the closing of the valve may be reestablished, thus requiring positive manipulation of the valve before a 30 resumption of gas flow can take place and at the same time indicating to the house holder the condition of affairs.

A still further object of the invention is to provide a gas cut-off which is simple of 35 construction, positive, reliable and efficient in action, and which affords convenience in the assemblage and repairs of the parts thereof.

The invention consists of the features of 40 construction, combination and arrangement of parts herein fully described and claimed, reference being had to the accompanying drawings in which:—

Figure 1 is a vertical section through the 45 safety cut-off on the line 1—1 of Fig. 3. Fig. 2 is a vertical section on the line 2—2 of Fig. 3. Fig. 3 is a sectional plan view on the line 3—3 of Fig. 1.

The device comprises a body or casing 1, 50 having a gas inlet 2 and a gas outlet 3, threaded for respective connection with the sections of a service pipe leading from the main to the service system of the house or building, respectively. The interior of the 55 casing provides a gas pressure chamber 4, and said casing is provided at one side with

an offset 5, for a purpose hereinafter described. A bonnet 6 is detachably secured to and closes the top of the casing, and serves as a container for the valve-controlling 60 parts of the appliance. The bonnet has an offset 7, corresponding in dimensions to the offset 5 and which overlies the same, as shown. The chamber 4 communicates with the outlet 3 through a restricted passage 8, 65 and said passage is controlled by a gravity cut-off valve 9 adapted to close against an inclined valve seat 10, the valve and seat having a ground-joint connection. The valve is in the form of a disk or plate and 70 seats in an inclined position and is preferably provided with a weight 11, adapting it to close with a desired rapidity. The valve is secured to shaft 13, extending outwardly from the casing through stuffing boxes 14 75 and provided at its outer end with a handle or hand wheel 15, whereby said shaft may be turned to manually open the valve. The offsets of the casing and bonnet form a compartment through which the shaft 13 extends, and secured to the shaft within said compartment is a collar 16 having a bearing surface 17 and a segmental latch member 18 provided with a shoulder 19. A leaf spring 20 is secured at its upper end within the offset of the bonnet and bears at its lower free 80 end against the bearing surface 17, the pressure of said spring, combined with the weight of the valve 9, serving to quickly and positively close said valve when released for 85 closing movement. A second rock shaft 21 is journaled in suitable bearings in the bonnet and its offset, and its end within the bonnet is provided with a latch arm 22 having a shoulder 23 to engage and interlock with 90 the shoulder 19 of the latch member 18 when the valve is in open position, and by means of which latch mechanism the valve is normally held open against the weight of the valve and the pressure of the spring. The 95 end of the rock shaft 21 which extends into the bonnet body carries a trip arm 24 which engages a beveled trip shoulder 25 on the adjacent arm 26 of a controlling lever 27, the other arm of which lever has pivotally 100 connected thereto the vertically disposed stem 28 of a pressure and gravity-controlled piston or diaphragm 29, the first-named arm of the lever being pivotally mounted within the bonnet and said lever being pivotally mounted 105 within the bonnet and said lever being pivotally supported intermediate of its ends upon a rocker link 30, whereby the diaphragm is

permitted to have free vertical movement. The diaphragm controls a pressure equalizing port 31 establishing communication between the bonnet and chamber 4, and is 5 adapted to close upwardly against a seat 32 to cut off the communication normally between the bonnet and pressure chamber. The bonnet is provided with a vent passage 33 to permit of the escape of gas therefrom 10 upon the closure of the valve, said passage being controlled by a check valve 34, whereby the access of foreign particles to the interior of the bonnet is prevented.

The piston or diaphragm is of a predetermined weight, and is normally held elevated by the pressure of the gas in the chamber 4, and remains elevated until the pressure in said chamber decreases to a predetermined degree, say to one-half ounce to the square 15 inch, at which time the weight of the diaphragm forces it downward, thus tilting the arm 26 of the controlling lever to force the trip arm 24 upwardly and outwardly.

It is understood, of course, that the valve 25 9 is manually opened by turning the shaft 13, and is locked in open position by engagement of the latch 24 with the latch member 18, such positions of the parts being maintained when the gas at normal pressure 30 is being supplied to the service system. Upon the reduction of pressure in the chamber 4 to the predetermined degree, and the dropping down of the piston or diaphragm, the latch 24 is elevated and moved out of 35 engagement with the latch member 18, whereupon the valve 9 drops by gravity and the force of the spring 20 and cuts off the flow of gas to the service system, the excess gas in the bonnet venting to the atmosphere 40 through the passage 33. The valve 9 being closed, no further supply of gas to the service system can take place until said valve is again manually opened and latched in open position, thus preventing 45 the flow of gas through the burners into the building under the conditions mentioned when normal pressure is reestablished.

As will be evident, the bonnet may be easily detached and affords ready access to 50 the working parts so that they may be cleansed or repaired or renewed as occasion requires.

I claim:

1. In a safety gas cut off, the combination 55 of a casing having a pressure chamber provided with an inlet and an outlet, the outlet having a valve seat, a rock shaft extending at one end exteriorly of said pressure cham-

ber, a weighted valve carried by said shaft and adapted to close against said valve seat, 60 a second rock shaft parallel with the first named shaft, a latch device upon the first named shaft, a latch member upon the second named shaft adapted for engagement with the latch device to hold the valve 65 open, a spring acting upon the latch device to assist in closing the valve when released by the latch element, a controlling arm on the second named rock shaft, a rock link, a lever pivoted to the link and having an inclined surface adapted for engagement with the controlling arm, and a pressure controlled diaphragm connected with said lever for adjusting the same to move the arm to shift the second-named rock shaft to a position to retract the latch element.

2. In a safety gas cut off, the combination of a casing having an inlet and outlet, the latter being provided with a valve seat, a rock shaft extending at one end exteriorly 80 of the casing, a weighted gravity controlled valve carried by said shaft, an offset at one side of the casing through which the exteriorly projecting end of the rock shaft extends, a bonnet in communication with the casing and having a complementary offset, said offset forming a compartment, a second rock shaft journaled in the bonnet and compartment, a latch device upon the portion of the first named rock shaft inclosed within 85 the compartment, a latch arm upon the portion of the second named rock shaft inclosed in the compartment, said latch arm being adapted for engagement with said latch device to hold the valve open, a spring acting 90 on the latch device to assist in closing the valve when said latch device is disengaged from the latch arm, a controlling arm upon the second named rock shaft within the bonnet, a controlling arm within the 100 bonnet, a lever pivotally mounted upon the rocker arm and having an inclined surface engaging the controlling arm for tilting said arm under prescribed conditions to release the latch arm, and a pressure controlled device influenced by variations of 105 pressure in the casing for adjusting the lever to effect tilting of the controlling arm when the pressure in the casing falls to a predetermined degree.

In testimony whereof I affix my signature in presence of two witnesses.

RALPH A. WAXLER.
